COMBINED MOTOR SUPPORT AND FAN GUARD MOUNTING

Joseph A. Lechtenberg, Kansas City, Mo.

Application September 29, 1947, Serial No. 141,652

Term of patent 3½ years

(Cl. D26—7)

To all whom it may concern:

Be it known that I, Joseph A. Lechtenberg, a citizen of the United States, residing at Kansas City, in the county of Jackson, and State of Missouri, have invented a new, original, and ornamental Design for a Combined Motor Support and Fan Guard Mounting, of which the following is a specification, reference being had to the accompanying drawing, forming a part thereof.

Figure 1 is a front elevational view of the combined motor support and fan guard mounting, showing my new design.

Fig. 2 is an edge elevational view thereof;

Fig. 3 is a rear elevational view thereof; and
Fig. 4 is a top plan view thereof.

I claim:

The ornamental design for a combined motor support and fan guard mounting, as shown.

JOSEPH A. LECHTENBERG.
